PRODUCTION OF OIL

Wilson G. Eris, Napoleonville, La., assignor to The Texas Company, New York, N. Y., a corporation of Delaware

Application September 16, 1943, Serial No. 502,663

7 Claims. (Cl. 103—232)

This invention relates to a method of pumping oil from subsurface formation; more particularly, the invention relates to a gas-lift method of pumping crude oil tending to deposit paraffin whereby production of the oil is accomplished efficiently and the deposition of paraffin is reduced or prevented.

When the natural flow of crude oil from a well has ceased or become too slow for economical production, artificial production methods are employed, and in many cases, it is advantageous, at least during the first part of the artificial production period, to employ gas lift. Numerous types of equipment for producing oil by gas lift are available, but they all rely upon the same general principles of operation. In the usual case, dry gas consisting essentially of methane and ethane is forced down the annulus between the tubing and the casing and into the oil in the tubing. As the oil in the tubing becomes aerated with gas, the density of the oil decreases, and eventually the weight of the column of aerated oil in the tubing becomes less than the pressure exerted on the body of oil in the well, and flow of oil occurs at the surface. While in some cases the dry gas may be introduced through the tubing so as to cause production through the annulus, this is not preferred unless special conditions are present.

It has been recognized that gas-lift methods for producing crude oil are of questionable value when the oil tends to deposit paraffin. This is because it has been found that paraffin deposition in a gas-lift well is particularly heavy. Accordingly, it has been frequently been decided not to use gas-lift methods because the expense of controlling paraffin deposition would more than offset any advantages obtained through the use of these methods.

An important problem encountered in producing a well by gas lift arises in starting the flow of oil. The gas-lift systems available on the market generally comprise an arrangement of valves in the tubing whereby the gas may be introduced first into the upper part of the column of oil in the tubing and then at lower points so that it is not necessary to raise the entire column of oil in the tubing a substantial distance prior to the mixture of the gas with the oil. These systems of gas lift satisfactorily accomplish the object of lessening the problem of starting production. When the crude oil being produced tends to deposit paraffin, however, the presence of the valves makes the job of cleaning paraffin from the tubing more difficult.

With the foregoing problems in mind, it is a principal object of the present invention to provide a method of producing crude oil tending to deposit paraffin by gas lift, whereby the oil may be produced efficiently, while, at the same time,

the deposition of paraffin is reduced or prevented.

Other objects of the invention will in part be obvious and will in part appear hereinafter.

I have discovered in accordance with the invention that crude oil tending to deposit paraffin can be produced by gas lift while avoiding troubles due to paraffin deposition, provided a gas is utilized which contains light hydrocarbons dispersed therein in the liquid phase. As pointed out above, the dry gas which is conventionally used is composed essentially of methane and ethane, and any small amount of other hydrocarbons that may be present in the gas are in the vapor phase under the conditions at which the dry gas is employed for gas lift. In the method of the invention, I employ a mixed fluid which comprises an amount of liquefiable hydrocarbons such that an important proportion of these hydrocarbons are present in the liquid form under the pressure and temperature conditions existing at the time of gas lift; the particular amount required for the desired reduction or prevention of paraffin deposition being dependent upon the specific conditions of production in the oil well and the characteristics of the liquefiable hydrocarbons.

The liquefiable hydrocarbons may vary in composition; for example, hydrocarbon mixtures such as a petroleum ether or light naphtha fraction of petroleum, natural gasoline, and hydrocarbons other than methane and ethane present in a fluid flowed from a distillate or condensate well may be employed as the liquid phase material in the gas. Thus, the hydrocarbons in the gas, other than methane and ethane, preferably comprise hydrocarbons containing not more than 8, particularly from 4 to 8, and especially from 3 to 8 carbon atoms. The dispersed liquid hydrocarbons may and usually will also include heavier hydrocarbons. Hydrocarbons containing 3 or more carbon atoms are conventionally referred to as liquefiable hydrocarbons, because, although the lighter members such as the C₁ and C₂ hydrocarbons may be gases under atmospheric conditions, they can be obtained in liquid form from a wet gas such as a distillate fluid by conventional recovery methods.

The method of the invention may be practiced in various ways. The liquid hydrocarbons which it is desired to have present in the gas may be injected into the usual dry gas to be used in gas lift, preferably in such manner as to effect dispersion of the liquid hydrocarbons throughout the gas. This may be accomplished by any conventional means. For example, the liquid hydrocarbons may be injected through an aspirator nozzle into the gas at the pressure required in the gas-lift operation. The dry gas may be gas from a natural gasoline plant which has been compressed to the desired pressure, gas from a high-pressure gas well, or residue gas from a dis-

tillate recovery plant. Gases of the latter types ordinarily will be at a sufficiently high pressure to permit their being used without compression.

When practicing the method in this way, the liquid hydrocarbon mixture employed may be any of the classes of mixtures referred to above. It is preferred to use a mixture of this type which contains a substantial proportion of propane and butanes in addition to the other hydrocarbons normally included in such mixtures. Thus, if natural gasoline or distillate is used as the liquid hydrocarbon mixture, it is preferred that it not be subjected to weathering, which would permit evolution of propane and butanes.

I have found that the method of the invention can be carried out in a particularly effective manner in areas where suitable wells are available by utilizing as the gas for accomplishing gas lift a distillate fluid containing the normally gaseous and liquefiable hydrocarbons present in the hydrocarbon mixture in the distillate reservoir. As is well-known, a distillate reservoir is characterized by containing a hydrocarbon mixture substantially entirely in a single homogeneous phase. The reservoirs are under high pressures; for example, pressures ranging from 2,000 to 5,000 pounds per square inch and above. Upon reducing the pressure and temperature of a distillate fluid, substantial condensation of liquefiable hydrocarbons occurs due to the phenomenon of retrograde condensation and also the normal temperature effect. The pressures required for gas lift operations are such that substantial condensation of liquefiable hydrocarbons occurs on reducing the pressure on a distillate fluid to the pressure of gas lift, and these condensed liquefiable hydrocarbons will include propane and butanes as well as higher boiling hydrocarbons. A distillate fluid is usually employed in accordance with the invention by flowing the fluid from a distillate formation, reducing the pressure on the fluid by means of a pressure-reducing valve located either at the surface or in the distillate well to the pressure of gas lift, and then passing the resulting fluid containing dispersed liquid hydrocarbons into the well or wells to be produced by gas lift.

The manner in which the invention may be practiced utilizing a distillate fluid is illustrated in the accompanying drawing in which the single figure is a more or less diagrammatic view, partly in section, showing an oil well, surface equipment, and a distillate well utilized in causing flow of the oil well.

Referring to the drawing, the well A is an oil well producing crude oil tending to deposit paraffin, and the well B is a distillate well which produces a fluid at a high pressure within the retrograde condensation range of the constituents of the fluid, this pressure being above the pressure of gas lift. The well A is equipped with a casing 10 which is perforated opposite the producing formation, as shown at 12. Disposed in the casing is a flow tubing 14 which is equipped with conventional devices for accomplishing gas lift in the tubing. Thus, there is a packer 16 which closes the annular space between the tubing and the casing, a standing valve 18, a bull plug 20, and three valves 22, 24, and 26, which furnish communication between the annular space above the packer and interior of the flow tubing. These valves are controlled by a cylindrical bar (not shown) disposed in the tubing which may be raised and lowered from the surface by means of a wire 28 which is operated by any suitable

means not shown. The bar, on being placed opposite a valve, opens that valve. In the arrangement shown, valves 22 and 24 are starting valves, and the valve 26 is a flow valve.

When the system disclosed is in regular operation, the distillate fluid is flowed from the well B through line 30 controlled by valve 32. Under normal circumstances, the fluid issuing from this well will comprise a mixture of normally liquid and normally gaseous hydrocarbons, part of which are in the gas phase and part of which are in the liquid phase. When the pressure on the fluid entering the line 30 is at a pressure above the pressure of gas lift, the valve 32 is employed as a pressure-reducing valve. The resulting mixed fluid is flowed into the annular space between the casing and the tubing and periodically is permitted to pass into the flow tubing through valve 26, this valve being opened and closed at regular intervals to permit the alternate filling of the tubing with oil and the flow of oil to the surface by means of the gas lift. By the arrangement shown, the distillate fluid containing the dispersed liquefied hydrocarbons enters the crude oil and functions to lift the oil to the surface, while, at the same time, reducing or preventing the deposition of paraffin.

The use of a distillate fluid in practicing the present process has other advantages. The liquefiable hydrocarbons present in the distillate fluid are absorbed in the crude oil so that the liquid product from the distillate well and the crude oil from the oil well may be handled efficiently in one stream. There is no loss of light components since after the crude oil has been passed through a conventional separator, the gases obtained may be treated in a natural gasoline plant for recovery of liquefiable constituents.

Distillate fluids vary in composition, but they are all characterized in that they contain a substantial proportion of hydrocarbons containing 3 to 8 carbon atoms and in that an important proportion of these hydrocarbons are in the liquid phase at the pressure and temperature conditions of gas lift. In starting gas-lift operations it is sometimes necessary initially to employ pressures as high as 1500 pounds per square inch, but after flow has started, it is customary to employ pressures below 750 pounds per square inch, for example, pressures from 125 to 500 pounds per square inch. While distillate fluids generally will contain more liquid phase material at higher pressures, at pressures of the order of 500 pounds per square inch and at atmospheric temperatures, they still contain important amounts of liquid phase material. A representative distillate fluid was found to have the following composition:

	Component	Mol. fraction
60	Methane	0.95173
	Ethane	0.01219
	Propane	0.00846
	Isobutane	0.00274
	n-Butane	0.00352
	Iso-pentane	0.00171
65	n-Pentane	0.00109
	Hexanes	0.00202
	Heptanes	0.00247
	Octanes and heavier	0.00016
	Carbon dioxide	0.00491

70 In the well from which this fluid was flowed, the bottom hole pressure was about 5000 pounds per square inch and the temperature about 212° F. Tests showed that both at 40° F. and 100° F. maximum liquid condensation occurred in the neighborhood of 1000 pounds per square inch.

but that at 600 pounds per square inch the fluid at 40° F. had a liquid volume of 0.00198 cubic foot per pound and at 100° F. a liquid volume of 0.00154 cubic foot per pound.

The method of the invention has been practiced successfully for the production of crude oil from a well in Louisiana. This well was particularly troublesome from the standpoint of paraffin deposition during the period of natural flow. Paraffin removal costs for the seven months preceding the cessation of flow averaged about thirty-three dollars per month. A conventional gas-lift system was installed when the flow ceased. The gas for gas lift was obtained from a distillate well in the vicinity, and the entire distillate fluid was introduced into the oil well. The pressure on the distillate fluid was reduced to about 500 pounds per square inch by means of a valve in the distillate well. This reduction in pressure and concomitant reduction in temperature caused substantial condensation of liquid hydrocarbons, tests showing that at the rate the well was flowed about 2.40 barrels of liquid hydrocarbons were being introduced into the oil well during each 24 hours of operation. These hydrocarbons included propane through octanes and heavier.

The oil well was produced at a rate of about 45 barrels per day for an extended period and no difficulties due to paraffin deposition were experienced. Inasmuch as it would normally be expected that when placing a well on gas lift, paraffin troubles would increase rather than decrease, this result indicates that the present method represents an important step forward in the production of crude oils tending to deposit paraffin by gas-lift procedures.

It will be understood that the amount of liquid hydrocarbons required to be used will vary in each case depending upon the type of crude oil, equipment in the well, depth of the well and other factors. Accordingly, this amount should be determined by tests in each case. Information obtained in developing the present invention has indicated that when an ordinary distillate fluid is used, an excess of liquid hydrocarbons will be present. This, of course, is not a disadvantage because the excess is recovered along with the crude oil. For example, tests have indicated that in the above well a fluid containing an amount of liquid phase material corresponding to 5 to 10 gallons per 24 hour period would be satisfactory. Although when the production from a distillate well is used in the process, there will usually be present more than enough liquid phase material to accomplish the objects of the invention, it will be understood that in a case in which this liquid phase material is insufficient additional liquid hydrocarbons may be added.

Obviously many modifications and variations of the invention, as hereinbefore set forth, may be made without departing from the spirit and scope thereof, and therefore only such limitations should be imposed as are indicated in the appended claims.

I claim:

1. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising a substantial proportion of hydrocarbons which are in the liquid phase at

atmospheric temperature and pressure, whereby the crude oil is aerated and is caused to flow to the surface while avoiding substantial deposition of paraffin.

5. 2. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing not more than 8 carbon atoms and a substantial proportion of hydrocarbons which are in the liquid phase at atmospheric temperature and pressure, and being present in amounts sufficient to prevent substantial deposition of paraffin in the well, whereby the crude oil in the well is aerated and caused to flow to the surface while avoiding substantial deposition of paraffin.
10. 3. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 3 to 8 carbon atoms and a substantial proportion of hydrocarbons which are in the liquid phase at atmospheric temperature and pressure, and being present in amounts sufficient to prevent substantial deposition of paraffin in the well, whereby the crude oil in the well is aerated and caused to flow to the surface while avoiding substantial deposition of paraffin.
15. 4. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
20. 5. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing not more than 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
25. 6. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
30. 7. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
35. 8. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
40. 9. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
45. 10. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
50. 11. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
55. 12. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
60. 13. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
65. 14. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
70. 15. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.
75. 16. In the process of producing from a subsurface reservoir by gas lift a crude oil tending to deposit paraffin, the improvement which comprises introducing from the surface into an oil well tapping the crude oil reservoir, under the pressure required for gas lift, a mixed fluid comprising a gas and liquefiable hydrocarbons in the liquid phase dispersed in said gas, said liquefiable hydrocarbons comprising hydrocarbons containing 4 to 8 carbon atoms and a substantial proportion of hydrocarbons which are in the liquid phase at atmospheric temperature and pressure, and being present in amounts sufficient to prevent substantial deposition of paraffin in the well, said mixed fluid being obtained by mixing with a gas comprising normally gaseous hydrocarbons a hydrocarbon mixture in liquid phase comprising hydrocarbons containing 4 to 8 carbon atoms, whereby the crude oil in the well is aerated and caused to flow to the surface while avoiding substantial deposition of paraffin.

drocarbons a hydrocarbon mixture in liquid phase recovered from a fluid flowed from a well tapping a distillate formation, whereby the crude oil in the well is aerated and caused to flow to the surface while avoiding substantial deposition of paraffin.

6. In the process of producing from a subsurface reservoir by gas lift a crude oil tending to deposit paraffin, the improvement which comprises introducing from the surface into an oil well tapping the crude oil reservoir, under the pressure required for gas lift, a fluid which comprises the production from a well tapping a distillate formation and consists of a mixed fluid comprising normally gaseous hydrocarbons in the vapor phase and liquefiable hydrocarbons in the liquid phase dispersed in said gas, said liquefiable hydrocarbons comprising a substantial proportion of hydrocarbons which are in the liquid phase at atmospheric temperature and pressure, whereby the crude oil in the well is aerated and caused to flow to the surface while avoiding substantial deposition of paraffin.

7. In the process of producing from a subsur-

face reservoir by gas lift a crude oil tending to deposit paraffin, the improvement which comprises reducing the pressure on a fluid flowed from a well tapping a distillate formation from the pressure of the distillate formation to the pressure of gas lift, whereby the distillate fluid is converted to a mixed fluid comprising normally gaseous hydrocarbons in vapor phase and liquefiable hydrocarbons in liquid phase dispersed in said vapor phase, said liquefiable hydrocarbons comprising a substantial proportion of hydrocarbons which are in the liquid phase at atmospheric temperature and pressure, introducing said mixed fluid into an oil well tapping the crude oil reservoir, under said pressure of gas lift, whereby said crude oil is aerated and caused to flow to the surface while avoiding substantial deposition of paraffin, said crude oil containing dissolved therein liquefiable hydrocarbons of said mixed fluid, and recovering said crude oil containing said liquefiable hydrocarbons of said mixed fluid.

WILSON G. ERIS.
